UNITED STATES PATENT OFFICE.

ISABELLE BASSETT, OF TAUNTON, MASSACHUSETTS.

DESIGN FOR A PLUME.

43,748.

Specification for Design.

Patented Apr. 1, 1913.

Application filed December 27, 1912. Serial No. 738,960. Term of patent 3½ years.

To all whom it may concern:

Be it known that I, ISABELLE BASSETT, a citizen of the United States, residing at Taunton, in the county of Bristol and State of Massachusetts, have invented a new, original, and ornamental Design for Plumes, of which the following is a specification, reference being had to the accompanying drawings, forming a part thereof.

The figure is a perspective view of a plume, showing my new design.

I claim:

The ornamental design for a plume, as shown.

ISABELLE BASSETT.

Witnesses:

W. B. O'NEILL,
SUSIE M. TUTTLE.
